SHOE SOLE

Harry Laybolt, Brockton, Mass., assignor to
 Plymouth Rubber Company, Inc., Canton,
 Mass., a corporation of Massachusetts

Application August 5, 1933, Serial No. 683,788

11 Claims. (Cl. 36—32)

This invention relates to a molded shoe sole of resilient material such as rubber or the like. An object of the invention is to provide a non-slip sole which, while suitable for various kinds of shoes, is more particularly for athletic shoes such as shoes for basket ball.

A sole embodying the present invention is characterized by a lateral flange of reduced thickness extending around the contour edge of the ball portion of the sole, and also, if desired, around the shank and heel portions, this flange being of reduced thickness and being flush upon its upper surface with the upper face of the sole. This flange is intended to hold the stitches by which the sole is sewed to a shoe upper. Since the flange is of reduced thickness, its lower face is offset from the lower face of the sole so that the stitches exposed at the lower face of the flange are thus kept out of contact with the floor and saved from wear. In sewing a sole of rubber or similar resilient material to a shoe upper, and more particularly in sewing the flange of a flanged rubber sole to a shoe upper, the material is liable to creep under the action of the sewing machine, causing more or less gathering of the sole at its margin which distorts the finished shoe. According to the invention, such creeping of the sole or flange is obviated by the provision of an uneven lower face on the flange itself. More specifically, I may provide on the lower face of the flange a series of corrugations or spaced transverse ridges to prevent such creeping under the action of the sewing machine, but the invention is not limited to any specific configuration of the bottom face of the flange.

Another object of the invention is to provide a non-slip bottom surface for the ball and heel portions of the shoe sole. To this end, I mold the sole with the bottom face of the ball portion substantially covered with small raised rings or circular ridges which surround and define shallow craters, the bottom centers of these craters being approximately in the same plane as the surface areas between adjacent rings, or slightly above such plane. The heel portion of the sole may also, if desired, be considerably covered with similar rings or circular ridges.

It is a further object of the invention to provide a sole of varying thickness such that the thickness tapers gradually from the longitudinal median line of the sole toward both side edges, the taper in thickness from the center of each edge being relatively small but sufficient to cause initial wear of the sole to take place along the longitudinal central portion of the ball and heel of

the sole. The taper in thickness from the median line toward the side edges is preferably more pronounced in the shank portion of the sole than in the ball and heel portions. As a result of this, the sole, when on a shoe, gives the appearance of an instep arch at the shank of the sole, but at the same time provides a continuous central line of support for the instep of the foot by contact of the shank portion of the sole with the floor along its median line. As a result of the difference of thickness between the mid portions and the edge portions of the ball and heel of the sole, the circular ridges or rings on the central portion of the ball and heel are the first to wear. As these wear down, the circular ridges and craters nearer the edges of the ball and heel become effective so that the non-slip characteristics of the shoe sole are retained through a considerable period of wear.

Shoe soles embodying the invention are also characterized by an increase of thickness at the ends thereof, this being for the purpose of offsetting the extra severity of wear which usually occurs at the toe and heel of shoes, especially athletic shoes.

For a more complete understanding of the invention, reference may be had to the description thereof which follows and from the drawing of which

Figure 1 is a bottom plan view of a shoe sole embodying the invention.

Figure 2 is a section on the line 2—2 of Figure 1.

Figure 3 is a section on the line 3—3 of Figure 1.

Figure 4 is a fragmentary section on a larger scale, this section being taken on the line 4—4 of Figure 1.

Figure 5 is a fragmentary section on the line 5—5 of Figure 1.

Figure 6 is a section on the line 6—6 of Figure 1.

Figure 7 is a bottom plan of a shoe sole of a slightly different form.

Figure 8 is a section on the line 8—8 of Figure 7.

Figure 9 is a bottom plan view of another modified form of shoe sole.

Figure 10 is a section on the line 10—10 of Figure 9.

The sole illustrated in Figures 1 to 6 inclusive is preferably a molded sole having a ball portion 10, a shank portion 11 and a heel portion 12. The sole is preferably made of a layer 13 of soft resilient rubber on the bottom, and a layer 14 of stiffer material, such as a rubber and fiber mix-

- ture, on the top, these layers being molded together in a unitary structure. As shown in Figure 1, a flange 15 may extend around the entire periphery of the sole, this flange being integral with the sole and projecting laterally from the contour edge thereof. As indicated in Figures 2, 3 and 6, the upper face 17 of the flange 15 is flush with the upper face of the sole itself, the lower face 18 of the flange being upwardly offset from the lower face of the shoe sole, so that, when the shoe is resting on the floor, the lower face 18 of the flange is spaced from the floor and the stitches exposed thereon thus protected from wear. The lower face 18 of the flange is made uneven in order to avoid creeping of the edge of the sole when it is being sewed to the shoe upper. The unevenness may be obtained in various ways. As shown, it consists of a series of ribs or ridges 20 extending transversely across the lower face 18 of the flange.
- The ball portion 10 of the sole is preferably provided on its bottom face with a number of rings or circular ridges 25 surrounding and defining shallow craters 26. These rings may be of the order of $\frac{1}{8}$ inch or so in diameter. The bottom centers 27 of the craters 26 are approximately in the same plane as the surface areas 28 between adjacent rings 25, but these craters may be slightly offset from the plane of the area between the rings, as indicated in Figure 4. The rings 25 are molded integral with the sole itself and serve to grip the floor or other surface upon which the shoe is used.
- The shoe sole may be further characterized by varying thickness. As indicated in Figures 3 and 6, the thickness of the sole on any transverse section thereof is maximum at the center as at 30 and tapers off slightly toward the side edges as at 31. This tapering towards the side edges may occur for substantially the entire length of the sole, the amount of taper being preferably of the order of one or two irons. As indicated in Figure 2, there may also be a gradual thickening of the sole toward the toe end as at 33 and also toward the heel end as at 34. This provides extra material for the sole at the two points which are subjected to severe wear, especially when the sole is used on a gymnasium shoe or the like. This increase in thickness toward the toe and heel ends of the sole may result in an increase of thickness of the flange 15 at the toe and heel ends of the sole as at 35 and 36, the distance of offset between the lower faces of the flange and sole being constant throughout the entire length of the flange; or the extra thickness may, as shown in Figure 10, result in a greater distance of offset between the flange and sole faces of the toe as at 38, the thickness of the flange 15 remaining constant throughout.
- Figures 7 and 8 illustrate a shoe sole similar to that illustrated in Figure 1, except that it has a heel 40 of the wedge type, this heel being of considerably more substantial thickness than that illustrated in Figure 1.
- In the form of sole illustrated in Figures 9 and 10, the heel portion 45 is made with a plane lower face having no flange on its periphery. This heel portion is adapted to receive a separate heel which can be secured thereto in the usual manner.
- It is evident that many modifications and changes may be made in the details of structure shown and described without departing from the spirit or scope of the invention as defined in the following claims.

I claim:—

1. A shoe sole of resilient material having a lateral flange of reduced thickness on the edges of the ball portion thereof, the lower face of said flange having an uneven surface whereby creeping is prevented when the sole is being sewed to a shoe upper. 80
2. A shoe sole of resilient material having a ball portion, a shank portion and a heel portion, a laterally projecting flange of reduced thickness around the entire contour of the sole and flush with the upper surface thereof, the lower face of said flange having an uneven surface whereby creeping is prevented when the sole is being sewed to a shoe upper. 85
3. A shoe sole of resilient material having a lateral flange of reduced thickness on the edges of the ball portion thereof, said flange having corrugations on the lower face thereof whereby creeping is prevented when the sole is being sewed to a shoe upper. 90
4. A shoe sole of resilient material having a lateral edge of reduced thickness on the edges of the ball portions thereof, said flange having a series of transverse ridges extending across the lower face of said flange, whereby creeping is prevented when the sole is being sewed to a shoe upper. 100
5. A shoe sole of resilient material having ball, shank and heel portions, and a lateral flange on the entire contour edge of said sole, said flange having its lower face offset upwardly from the bottom of the sole, said lower face of the flange having an uneven surface, whereby creeping is prevented when the sole is being sewed to a shoe upper. 105
6. A unitary molded shoe sole having a bottom layer of soft rubber and a layer of stiffer material, said sole having a lateral flange of reduced thickness on the edges of the ball portion thereof, the lower face of said flange having an uneven surface whereby creeping is prevented when the sole is being sewed to a shoe upper. 115
7. A unitary molded shoe sole having a bottom layer of soft rubber and a layer of stiffer material, said sole having a lateral flange of reduced thickness on the edge of the ball portion thereof, said flange having its lower face offset upwardly from the bottom of the sole and provided with transverse ridges whereby creeping is prevented when the sole is sewed to a shoe upper. 120
8. A molded shoe sole having a gradual taper in thickness from the longitudinal median line toward both side edges, said sole having the bottom face of the ball portion thereof substantially covered by integral ridges surrounding and defining small shallow craters. 130
9. A molded shoe sole having a gradual taper in thickness from the longitudinal median line toward both side edges, said sole having the bottom face of the ball and heel portions thereof substantially covered by integral ridges surrounding and defining small shallow craters. 135
10. A molded shoe sole of varying thickness having a gradual increase in thickness in the toe and heel portions thereof toward the longitudinal extremities thereof. 140
11. A molded shoe sole varying in thickness, said sole having a gradual taper in thickness from the longitudinal median toward both side edges, and a gradual increase in thickness toward the longitudinal extremities thereof. 145

HARRY LAYBOLT.
